RAILWAY TRAFFIC CONTROLLING SYSTEM

Application filed August 16, 1921. Serial No. 492,643.

This invention relates to railway traffic controlling systems and has for an object to provide a cab signal in a locomotive and an automatic means for controlling the train when it exceeds a predetermined speed and when it enters an unsafe section of track. It has further for an object a means for securing a variety of effects on a locomotive inductively from devices placed on the track and controlled according to track conditions. Also it has for an object means for amplifying mechanically the effect transmitted by electromagnetic induction from the track device to the locomotive device. These and other objects will be more particularly understood from the following specification and the accompanying drawings in which Fig. 1 is a side elevation of one form of the track device, Fig. 2 is a plan view, Fig. 3 is an end view partly in section, of the mechanical amplifier for use with direct current, Fig. 4 is a plan view corresponding to Fig. 3, with the cover in section, Fig. 5 is a modified arrangement for use with alternating current, Fig. 6 shows a modified construction of the track device for use with alternating current, Figs. 7, 8, 9, 10 and 11 show an inductive device on the locomotive for producing the stop effect, Fig. 7 being a side elevation with the cover shown in section; Fig. 8 is an end elevation with the cover in section; Fig. 9 is a plan view with the cover in section, Figs. 10 and 11 are details of the operating magnet and counter weights. Fig. 12 shows an arrangement of circuits for applying my invention on a locomotive and Fig. 13 shows an arrangement for wiring the track apparatus for applying this invention.

This invention consists of three main parts; first, a device which I call a mechanical amplifier for receiving a proceed signal from the track device; second, a device which I call the stop magnet operating to control the train when under the influence of the track device and third, the application of the system.

The mechanical amplifier is a device which receives an effect inductively from the track device and amplifies this effect by mechani-

cal means on the locomotive, thereby producing considerable electric power, insuring reliable operation and permitting the use of comparatively rugged apparatus. The mechanical amplifier consists in its essential parts of an armature rotating at a high speed between a pair of magnetic poles which are normally demagnetized. When these poles come under the influence of the track device they are magnetized by electromagnetic induction and an electromotive force is generated in the rotating armature. The voltage generated by the rotating armature is proportional to the strength of the field and the speed at which the armature rotates. Thus, while the field under ordinary conditions is comparatively weak, this can be in a very large measure compensated for by high speed in the armature with the result that a considerable voltage is generated in the armature which is used to energize a relay to obtain any useful effect desired on the locomotive. If the rotating armature should for any reason stop then no voltage would be generated in it and it thus contains the means for detecting its own failure.

Referring to Figs. 1 and 2 showing the ramp, 11 represents a wooden stringer or base upon which the ramp members are supported, preferably on the end of the railroad ties. The ramp consists of a magnetic member 12 and a magnetic member 13 placed parallel to each other and parallel to the track. Between these members magnet coils are placed as indicated at 14 surrounding the cores 14a which thereby energize the plates 12 and 13. The coils are arranged so that each plate is energized with polarity opposite to the other plate. In the application of the system it is necessary to have these magnet coils at each end of the ramp but the magnet coils may be omitted in a space in the centre of the ramp as indicated at 15. Also, one of the ramp members may be discontinued for this space if desired as indicated by the dotted lines in Fig. 1.

The mechanical amplifier for operating on direct current is shown in Figs. 3 and 4. 21 represents the rotating armature, 22 and 23 are the magnetic pole pieces, 24 is the shaft 100

for the armature and 25 is a motor for driving the armature. This motor may be operated by compressed air, steam or other power, although in the present application an electric motor only is considered. The term "mechanical amplifier" has been applied to this device, as the armature may be driven from any source of mechanical power. It is assumed that this motor runs continuously at a high speed of say 2,000 revolutions per minute. However, this system may be applied with an arrangement which will bring this motor into operation only when the locomotive apparatus is under the influence of the track device.

The armature 21 is provided with brushes 26 and 27 forming the terminals of a circuit hereafter to be described. 28 is the pole piece for the pole 22 and 29 is the pole piece for 23. It will be noted from Fig. 4 that these pole pieces are comparatively long and are arranged to pass directly through the vertical planes of the plates 12 and 13 of the track device, the large area of these poles providing a greater area for the magnetic circuit and thus compensating to a considerable extent for the vertical air gaps in this circuit between plates 12 and 13 and the poles 28 and 29. A cover, 30, preferably of non-magnetic material is provided for this device, also a supporting plate 31 of brass or other non-magnetic material holds the parts in alignment and provides a dust-proof cover for the base of the device.

It should be noted that the direction of the current generated in the armature 21 depends upon the polarity of the pole pieces 22 and 23 which in turn depends upon the polarity of the plates 12 and 13. It is thus possible to operate a polarized relay connected to the terminals 26 and 27 as will be more fully described in connection with the application of the system. It is here pointed out that the mechanical amplifier, when influenced by a constant magnetic field, produces a sustained current in its armature for application to any useful purpose.

Figs. 5 and 6 show a modification of the mechanical amplifier adapted for use when the track device is energized by alternating current. In this arrangement the plates 12 and 13 are replaced by laminated plates 12a and 13a as indicated in Fig. 6; also the pole 33 is provided with a laminated plate 35 and pole 34 is provided with a laminated plate 36 held in position by the non-magnetic clamp 37. The pole pieces 33 and 34 are provided with flux retarding sections on the vertical axis indicated at 38 and 39. This may be an ordinary air gap as used in the D. C. arrangement or for manufacturing reasons it may be a reduced section of the iron as indicated at 38 upon which may be wound a coil or ferrule of copper which will set up a

reaction to the A. C. flux between the poles 33 and 34.

This device is built upon the principle of a two-phase induction motor in which the coils of the track device become one phase and a horizontal coil 40, inserted in the faces of the poles 33 and 34 is the other phase. It is a well-known fact that when an induction motor is running at synchronous speed the flux in the armature is uni-directional. A considerable portion of this flux is carried over to the other phase, generating an alternating electro motive force therein. For instance, if the track device is energized with a current at twenty-five cycles frequency and the rotor 32 is running at fifteen hundred revolutions per minute, it will be in synchronism. However, it is well-known that when a two-phase motor is running on single phase that an electro motive force is generated in the idle phase. This is briefly referred to in the Standard Hand-Book for Electrical Engineers, edition of 1915, section 16, paragraph 193. This will also be found in United States Patents #1,014,966, dated January 16, 1912 and #1,147,171, dated July 20, 1915.

The stop device consists of a magnet placed horizontally and having pole pieces extending downwardly in the vertical planes of the magnetic members of the track device. This magnet consists of a single coil pivoted in a mechanism case and partially balanced by a counter-weight. An armature or back strap is provided for these pole pieces which is also pivoted to the frame and balanced by a counter-weight. The arrangement of the counter-weights is such that when the magnet coil is deenergized the coil itself will overbalance the counter-weights and permit the pole pieces to drop to the lowered position. When, however, the coil is energized it attracts the armature and since they move on the same pivot the armature and coil move together as one part with, however, the difference that the combined counter-weights of the two will overbalance the magnet coil, with the result that the magnet coil is thereby raised unless some exterior condition is applied which causes it to move to the lowered position. This exterior condition is supplied by the magnetic plates of the track device which form a magnetic path alternative to the extended pole pieces, causing the magnet coil to move to the lowered position when passing over a track device. The reason for pivoting and counter-weighting the armature independently of the coil is to maintain the closed circuit principle in the application of the stop magnet.

When the stop magnet is in the raised position a circuit controller is raised to close certain circuits hereafter described to suspend the operation of the train control system. When this magnet is lowered these circuits

are interrupted and conditions are set up for bringing the train control system into operation unless other conditions are established to prevent this operation. When the armature is lowered, certain circuits are closed which operate a speed control device and also prevent the operation of the train control device during the time that a train is passing over the track device. The arrangement of these circuits is such that if the stop magnet becomes deenergized and releases its armature it by gravity falls to the lowered position and also the counter-weight of the armature assumes the lowest position and this sets the train controlling apparatus in operation and the circuits controlled by the armature are not established to prevent the operation of this apparatus. Hence, a failure of the stop magnet becomes self-detecting.

Referring to the drawings, 51 represents a locomotive wheel running on the rail 52 supported by the tie or sleeper 53 and having an axle box 54 with the bracket 55 secured thereto as shown, to support the stop magnet by the bolts 56 engaging the casing 58 as shown. Coil springs 57 may be provided on these bolts so that the entire mechanism will readily yield to any obstruction on the track without breakage. The ends of the casing 58 are sloped as shown at 72 and provided with a non-magnetic plate of manganese iron, brass or other material to enclose the magnet and the working parts without interfering with the magnetic operation of the apparatus. The core of the magnet 61 is shown at 60, Fig. 10, and is secured to a bracket 63 pivoted at 62 in the arm 65. Upon one of the legs of bracket 63, the counter-weight 64 and on the other leg the counter-weight 64a is mounted. These two counter-weights are arranged to counter-balance a large part of the weight of the magnet coil 61 and the associated parts without, however, overbalancing this coil but leaving a reasonable operating margin whereby the coil will have a bias to return to the downward position.

The magnet 61 is provided with a pole piece 66 at one end and a pole piece 67 at the other end. These pole pieces terminate in flat plates as shown which extend transversely over the magnetic plates 12 and 13 of the track device and being of considerable area, transmit the lines of force through the track device between these poles.

The upper ends of these poles are positioned near an armature 68, Fig. 11, preferably having a small air gap between itself and the poles. The design of the magnet 61 maintains substantially a constant magnetic flux through the armature 68 without being materially influenced by other magnetic circuits established between the poles 66 and 67. This armature is supported by a non-magnetic bracket 69 also carried on the pivot 62 and having a counter-weight 70 extending on

the opposite side. This counter-weight will not only overbalance the armature 68 but will also in combination with counter-weights 64 and 64a, overbalance the magnet 61 when the armature 68 is attracted by the poles 66 and 67. With this arrangement, therefore, and with magnet 61 energized, this magnet has a bias to remain in the raised position. This bias, however, is overcome by the magnetic plates 12 and 13 of the track device due to the magnetic flux through these plates from the poles 66 and 67, causing magnet 61 to move into the lowered position and thereby setting up conditions to operate the train control system. As soon as this magnet has passed over the ramp it immediately assumes the raised position, due to the bias of the counter-weights.

The base of the housing 58 is provided with a comparatively thin plate of non-magnetic material 72. This plate may be reinforced by the non-magnetic bars 71, thereby preventing it from being dented so as to interfere with the free movement of the magnet 61.

A circuit controller is operated by the magnet 61 and an independent circuit controller is operated by the armature 68. These circuit controllers are housed in the casing 75 and may be constructed of an insulating plate 76 having a row of contact members with contact fingers similar to 79a carried on the plungers 77 and 78. These contacts may be arranged to open or close a circuit by the movement of the magnet and the armature as will be more particularly explained in connection with the operation of the circuits. The plunger 77 connects directly to the counter-weight 70 and therefore responds directly to the movement of armature 68. Plunger 78 connects to the lever 79 pivoted at 80 and operated by a stud 82 on arm 83, Fig. 10, in the slot 81 so that as magnet 61 is raised this lever is raised together with the plunger 78 and as the magnet is lowered this lever is also lowered. The plungers are, therefore, operated by the magnet 61. The magnet 61 and the armature 68 are operated together so that as the magnet is lowered plunger 77 is raised but when magnet 61 is deenergized their operation becomes independent of each other and plunger 77 is lowered by the counter-weight.

When the magnet 61 becomes deenergized and afterwards becomes energized it may not have sufficient pull to raise itself to the armature 68. In this case, the armature may be manually restored by pressing upon the plunger 90.

Generally, it will be found that on a locomotive there are three forces acting upon a device of this character. First, the centrifugal force due to a train running on curves; second, the force due to the inertia of the moving parts when the train is stopping and starting and third, the vertical vibration due to low joints on the track. The first condition is overcome in the present invention by pivot-

ing the moving elements in line with the direction of the centrifugal force and therefore, they are not subject to disturbance from this cause. The second force, due to the inertia 5 of the moving parts when the train is stopping and starting is very largely neutralized by placing the pivot of the magnet and counter-weights in the same horizontal plane with the centre of gravity and the effect of the 10 third force, due to the vertical vibration which occurs at intervals is neutralized to a considerable extent by the balance of the parts on both sides of the pivot and is further reduced by the mass of the counter-weight 15 and the magnet, the entire arrangement providing a working device to meet the varying conditions to be met with on a railroad locomotive.

The application of this system will be understood from Fig. 12, showing the locomotive wiring and Fig. 13, showing the track wiring. 20 101 represents a relay having both a neutral and a polarized armature. This relay is controlled by wire 102, right hand mechanical amplifier 110, wire 103, left hand mechanical amplifier 110, wire 104, contact 105 operated by armature 68 when coil 61 is in the lowered position and wire 106. This relay, therefore, 25 is connected in series circuit with the right and left hand mechanical amplifiers and its 30 circuit is established only when the stop magnet is passing over a ramp. The latter insures that before a proceed signal can be obtained from the mechanical amplifiers the 35 stop magnet must have operated and in this way the operation of the stop magnet is detected every time a proceed signal is received. This system may be operated by one mechanical amplifier. However, by connecting two 40 in series the voltage is doubled and by placing these amplifiers one on each side of the stop magnet an amplifier will always engage the track device after the stop magnet has passed over the same when the locomotive runs in 45 either direction.

When magnet 101 is energized the neutral contacts 117 and 121 are raised to close circuits and the polarized contacts 115 and 119 respond to the direction of the current used 50 to energize the relay 101, which in turn is controlled by the direction of the current in the track device.

The mechanical amplifiers 110 are driven by the electric motors 25 connecting to the 55 bus mains 11 and 12 which are energized by generator 113. Magnet 61 is also energized from these bus mains as shown. The integrity of the circuits connected to these bus mains is necessary to establish safe running conditions.

The circuit of battery 114 is controlled by the polarized contacts of relay 101. In the position shown, one side connects to contact 115, wire 116, neutral contact 117 when relay 101 is energized, wire 118, block relay

123, wire 122, neutral contact 121, wire 120 and polarized contact 119 to the opposite side of battery 114. This energizes the block relay 123 and also controls its polarized contacts 125, 129, 146 and 152 in accordance with 70 the polarity in the wires 118 and 122. If relay 101 were energized from the mechanical amplifiers by a current such as to reverse the position of contacts 115 and 119, then the 75 polarity in wires 118 and 122 would be reversed and polarized contacts 125, 129, 146 and 152 of relay 123 would be reversed. Relay 123, is therefore, polarized and the 80 position of its polarized contacts is indirectly responsive to the polarity of the current used to energize the track device.

The circuit for block relay 123 controlled by relay 101 is a pick-up circuit and remains energized only during the time the mechanical amplifiers are passing over a track device. 85 Relay 123, therefore, has a stick circuit controlled by the stop magnet 61 comprising wire 134, neutral contact 133, wire 132, contact finger 131 operated by plunger 78, wire 130, polarized contact 129, battery 124, polarized contact 125, wire 126, neutral contact 127 and wire 128. This maintains relay 123 energized by current of the same polarity as picked it up by the operation of relay 101. If current of the opposite polarity had been 90 used to pick up relay 123 then the polarized contacts would have been swung to the opposite side and the previous circuit would have been changed at polarized contacts 129 and 125, so that the block relay would be maintained energized by current of the opposite 95 polarity, holding the polarized contacts 125, 129, 146 and 152 in the position to which they were picked up. It will be noted that stop magnet 61 opens the contact 131 and battery 100 124 is thereby disconnected from energizing relay 123 and this relay will become deenergized unless the pick-up relay 101 is energized from the mechanical amplifiers to re-establish the circuit through stick contacts 133 and 105 127. It will be apparent to those skilled in 110 designing circuits for this class of work that under certain conditions relays 101 and 123 may be combined. However, better operation is possible by the arrangement shown 115 in which the batteries used for energizing these relays are separated and it is possible to control the pick-up circuit by the stop magnet.

The main battery 141 connects on one side 120 to the battery wire 142 and on the opposite side to the common wire 143. When relay 123 is energized a circuit is established from wire 142 through neutral contact 144, wire 145 and polarized contact 146. When in the 125 position shown, a circuit is established to wire 147 operating the top light indicated by "G" of the signal 150 which on the opposite side connects to the common wire 143. Also when the polarized contact 146 is in the 130

- opposite position a circuit is established to wire 148 connected to the middle light of the signal 150 indicated by "Y" and when the relay 123 is deenergized, neutral contact 144 5 establishes a circuit to wire 149 connected to the bottom light of the signal device 150, indicated by the letter "R". This produces three distinct signals secured, first when relay 123 is energized and its armature is raised 10 and the polarized armature moved to the left; second, when the relay 123 is energized and its armature raised and the polarized armature moved to the right and third, when the relay 123 is deenergized. 15 A system of speed control operating a brake valve is included with the cab signal arrangement just described in the present invention. The speed control is obtained by a time element relay having a predetermined 20 time interval for closing a circuit and the circuit of which is set up by the stop magnet on passing a track device. The time element relay is indicated at 159, the brake valve is indicated at 166 and the brake valve 25 relay at 154. This latter relay is energized by a circuit operating in multiple with the circuit which energizes the "G" signal so that when this signal is displayed the operation of the train control apparatus is suspended. 30 This circuit may be traced from wire 145, wire 151, polarized contact 152, wire 153, relay 154, wire 143 to battery 141. When relay 154 is energized a stick circuit is established through contact 155, wire 156, 35 contact finger 157 of plunger 78, and wire 142 to battery so that each time the stop magnet is operated the stick circuit of relay 154 is interrupted. When, however, the stop magnet 61 moves to the down position, a circuit is established from battery wire 142 through contact 161 and wire 160 to the time element relay 159 and if contact 161 remains closed for a sufficient length of time, relay 159 will pick up 40 armature 158 and establish a circuit from wire 142 to wire 153 which picks up the brake valve relay 154 and thereby prevents the operation of the brake valve. This condition occurs when the train is running below a predetermined speed over the track devices. 45 The circuit of the brake valve 166 can be traced from common wire 143, wire 165, wire 164 and contact 163 of the brake valve relay 154 to battery wire 142, so that while this 50 relay remains energized the brake valve magnet is also energized. In order to maintain the brake valve magnet energized during the time the train is passing a track device, a circuit is established from wire 164 through 55 contact finger 167 operated by armature 68 to battery wire 142. The brake valve magnet is therefore deenergized only when a "Y" or "R" signal has been received and then only if a train exceeds a predetermined speed in 60 passing a track device and then it is not de- 65 energized until the stop magnet has passed completely over the track device. A manually operated push button 168 is provided for energizing relay 154 in order that the train may proceed after the operation of the 70 train control system. 75 In the application of the stop magnet it will be noted that certain circuits are controlled by the movement of the magnet itself, whereas other circuits are controlled by the movement of the armature 68. The circuits controlled by the magnet are those that lead to the deenergizing of the block relay and the brake valve relay and set up the conditions for train control, whereas the circuits operated by the armature 68 relate to the proceed signal, the direct control of the brake valve and the operation of the time element device to prevent the operation of the train control system. Moreover, it will be noted that armature 68 must be moved into an active position to close the circuits mentioned. If magnet 61, therefore, should become deenergized it drops by gravity and opens the holding circuit of the block relay and the brake valve relay while the circuits controlled by armature 68 remain inactive and open, thus leading to an immediate application of the train control system with an 80 "R" signal. 85 The track arrangement in Fig. 13 is designed to operate the locomotive apparatus as shown in the circuits in Fig. 12. The track rails 52 and 52a are divided into suitable block sections A, B, and C, separated by insulated joints to which the track battery 173 is connected at one end and the track relay 174 is connected by wires 175 and 176 at the opposite end according to standard practice in the operation of the well-known track circuit. The track devices are indicated by 90 171 and 172 and are energized by coils 14 as indicated. Each is wired alike and is shown with similar reference characters. The relay 179 connects to the common wire 178 and is controlled by wire 190, contact 189 of the track relay for the next section in advance, wire 188 when this relay is energized, to battery 180 and by wire 191 when this relay is deenergized to battery 181. These batteries have opposite poles connecting to the common wire and, therefore, energize the relay 179 by opposite polarity, thus controlling the position of polarized armature 185. When this armature is positioned to the left as 95 shown, a circuit is established from battery 181, wire 186, armature 185, wire 184, contact 183 of the track relay and wire 182 to the track device 172 which connects to common wire 178, also by line wire 182a to the track device 171 which also connects to the common wire 178. When the polarized armature 185 is moved to the right a circuit is established from battery 180 through wire 187, armature 185, wire 184 to track devices 171 and 172 as 100 105 110 115 120 125 130

just described. Therefore, the track devices are energized with current of different polarity, depending upon the position of the polarized armature 185 and the position of this armature depends upon the condition of the block. For instance, when blocks A and B are unoccupied the polarized armature 185 at the entrance to block A may be moved to the position shown, thereby giving a clear or "G" signal to the locomotive. When, however, block B is occupied, polarized armature 185 is moved to the right, with the result that the track devices are energized with opposite polarity which may be arranged to give a "Y" or caution signal on the locomotive and if block A is occupied its track relay will be deenergized and consequently the track devices will be deenergized so that no current is generated by the mechanical amplifiers while the stop magnet operates to deenergize the block relay and the brake valve relay, thus giving a red or stop signal and operating the train brakes.

It will be noted that the track device 171 is shorter than the track device 172 and therefore a train must consume a greater length of time in passing the device 171 in order to pick up relay 159, than is necessary in passing the device 172. A number of devices corresponding to 171 may be installed in the block, each progressively shorter in length as the train approaches the end of the block in order to insure a progressive reduction in speed.

It should be observed that in the application of this invention certain apparatus is provided on the trackway and other apparatus is provided on the vehicle. The vehicle is provided with devices which are responsive to the trackway apparatus inductively but the method of producing this inductive effect may assume a variety of forms well known in this art and the principles of the invention can be applied with such variations by those skilled in the art. The claims are not to be construed as limited to the construction shown but should be considered as covering a full range of equivalents.

Having thus described my invention, I claim:

1. In combination, a railway track, a vehicle thereon, a device on said track and a device on said vehicle, means whereby an electrical effect is transmitted between said devices, means whereby said effect is mechanically amplified by one of said devices into a direct current, the characteristic of said current corresponding with the characteristic of said effect.

2. In combination, a railway track, a vehicle thereon, a device on said track electrically controlled, a device on said vehicle having normally deenergized pole pieces and a rotating armature, means for energizing said poles inductively from said track device ac-

cording to a predetermined polarity whereby a current of a predetermined polarity is generated by said armature.

3. In combination, a railway track, a vehicle thereon, a device on said track electrically energized, a device on said vehicle having normally deenergized poles and a rotating armature, a polarized relay connected in circuit with said armature, means for energizing said poles inductively from said track device whereby a current is generated in said armature and means for operating said relay according to the polarity of the current energizing said track device.

4. In combination, a railway track, a device on said track capable of being magnetized, a vehicle on said track, an electric generator on said vehicle without a magnetic field and means whereby said track device supplies directly a magnetic field for said generator, thereby causing it to generate current.

5. In combination, a railway track, magnetic devices on said track having a pair of poles electrically energized, a vehicle on said track, an electric generator on said vehicle having a rotating armature, and a pair of poles without a field winding means whereby the poles of said track device align with the poles of said generator forming a field therefore and causing a current to be generated in said armature.

6. In combination, a railway track, magnetic devices on said track, a vehicle on said track, a plurality of electric generators on said vehicle, said generators having rotating armatures and poles without magnetic fields, means whereby the magnetic fields of said generators are directly supplied by said track devices, said armatures connected in series circuit and operating an electric translating device.

7. In combination, a railway track, a vehicle thereon, a magnetic device on said track, a magnet on said vehicle consisting of a horizontal coil pivotally supported at one end in a horizontal plane and balanced by a counterweight and downwardly extending poles associated with said coil arranged to pass through the vertical planes of said track device.

8. In combination, a railway track, a vehicle thereon, a magnetic device on said track, a horizontal magnet on said vehicle, said magnet pivoted at one end for vertical movement, a horizontal armature for said magnet independently pivoted for vertical movement, poles for said magnet, said poles passing through the vertical planes of said track device.

9. In combination, a railway track, a vehicle thereon, a magnetic device on said track, a magnet on said vehicle pivotally supported and counterweighted, an armature for said magnet pivoted independently of said

coil and counterweighted and poles for said coil passing through the vertical plane of said track device.

10. In combination, a railway track, a vehicle thereon, a magnetic device on said track, a pivotally supported magnet coil on said vehicle, a pivoted armature for said magnet, said armature counterweighted to lift said magnet coil, said coil being lowered by magnetic attraction when passing said track device.

11. In combination, a railway track, a vehicle thereon, a magnetic device on said track, a horizontal magnet coil with poles pivotally supported and an armature independently pivoted on said vehicle, a counterweight biasing said magnet coil to the raised position and said track device magnetically moving it to the lowered position.

20 12. In combination, a railway track, a vehicle thereon, a magnetic device on said track, a magnet on said vehicle consisting of a pivoted coil balanced with a counterweight and a pivoted armature balanced with a counterweight, said magnet when energized having a bias from said counterweight to raise it and when deenergized having a bias to lower it.

30 13. In combination, a railway track, a vehicle thereon, a magnetic device on said track, a magnet on said vehicle consisting of a pivoted coil balanced with a counterweight and a pivoted armature balanced with a counterweight, said magnet when energized having a bias to raise it and when deenergized, said armature remaining raised and said coil becoming lowered.

40 14. In combination, a railway track, a vehicle thereon, a magnetic device on said track, a magnet on said vehicle consisting of a horizontal coil having considerable mass, placed parallel with said track, downwardly extending poles aligning with said track device and associated with said coil, said magnet pivoted at one end in a plane parallel with said track and having a counterweight.

50 15. In combination, a railway track, a vehicle thereon, a magnetic device on said track, a magnet on said vehicle consisting of a horizontal coil placed parallel with said track and counterweighted, downwardly extending poles aligning with said track device and associated with said coil, said magnet pivoted in a horizontal plane parallel with said track and on the line of the centre of gravity of said coil and said counterweight.

60 16. In combination, a railway track, a vehicle thereon, a magnetic device on said track, a horizontal magnet on said vehicle consisting of a coil placed parallel with said track and counterweighted, downwardly extending poles aligning with said track device and associated with said coil, said magnet pivoted in a horizontal plane parallel with said track and on the line of the centre of gravity of

said coil and said counterweight, said magnet and counterweight having considerable mass and partially balanced on said pivot.

17. In combination, a railway track, a vehicle thereon, a magnetic device on said track, a magnet on said vehicle consisting of a horizontal coil placed parallel with said track, said coil having poles aligning with said track device, a lever arm, said magnet operating a circuit controller through said lever arm, said magnet pivotally mounted and partially balanced by a counterweight.

70 18. In combination, a railway track, a vehicle thereon, a magnetic plate on said track, a magnet on said vehicle having a horizontal pivoted armature with a counterweight, said magnet and armature enclosed within a case, said armature operating a circuit controller and means exterior to said case for manually resetting said armature to engage said magnet.

80 19. In combination, a railway track, a vehicle thereon, a magnetic device on said track, a pivoted magnet on said vehicle and an independently pivoted armature for said magnet, said magnet and armature moved on their pivots by said track device, the downward movement of said magnet opening a circuit and the downward movement of said armature closing a circuit.

90 20. In a railway traffic controlling system, the combination of a track, a vehicle thereon, a pivotally supported magnetic device on said vehicle and an independent pivoted armature for said device, a magnetic device on said track, a controlling mechanism, said vehicle device responding to said track device to operate said controlling mechanism and said armature responding to said vehicle device to prevent the operation of said controlling mechanism.

100 21. In combination, a railway track, a vehicle thereon, a pivotally supported magnetic device on said vehicle, an independently pivoted armature for said device, a magnetic device on said track, said vehicle device responding to said track device and means whereby the movements of said vehicle device and armature cooperatively open a circuit and close another circuit.

110 22. In combination, a railway track, a vehicle thereon, a pivotally supported magnetic device on said vehicle, an independently pivoted armature for said vehicle device, a magnetic device on said track, said vehicle device responding to said track device, a circuit controller operated by said magnetic device and another circuit controller independently operated by said armature.

120 23. In combination, a railway track, a vehicle thereon, a pivotally supported magnetic device on said vehicle, an independently pivoted armature for said vehicle device, a magnetic device on said track, said vehicle device responding to said track device, means

whereby said vehicle device when energized cooperates with said armature to operate a circuit controller and means whereby said vehicle device and armature operate circuit controllers independently when said device is deenergized.

24. In a railway traffic controlling system, the combination of a track, a vehicle thereon, a pivotally supported magnetic device on said vehicle and an independently pivoted armature for said device, a magnetic device on said track, a controlling mechanism, said vehicle device when energized, responding to said track device to operate said controlling mechanism, said armature responding to said vehicle device when energized to prevent the operation of said controlling mechanism and said vehicle device when deenergized operating said controlling mechanism.

25. In a railway traffic controlling system, the combination of a railway track, a vehicle thereon, a pivotally supported magnetic device on said vehicle and an independently pivoted armature for said device, a magnetic device on said track, said vehicle device responding to said track device, a train controlling mechanism, the circuit of said train controlling mechanism being interrupted by said vehicle device when responding to said track device and a circuit established by said armature to prevent the operation of said train controlling mechanism.

26. In a railway traffic controlling system, the combination of a railway track, a vehicle thereon, a device on said track and a device on said vehicle coacting with said track device, a normally deenergized, polarized relay on said vehicle, a polarized block relay on said vehicle and said normally deenergized polarized relay responding to the characteristic of the current in said track device through said vehicle device and correspondingly controlling said block relay.

27. In a railway traffic controlling system, the combination of a railway track, a vehicle thereon, a device on said track and a device on said vehicle coacting with said track device, a normally deenergized polarized relay responding to the characteristic of the current in said track device through said vehicle device, a polarized block relay controlled by said normally deenergized polarized relay, a stick circuit for said block relay, said stick circuit controlled by the polarized contacts of said block relay.

28. In a railway traffic controlling system, the combination of a track, a vehicle thereon, a pivotally supported magnetic device on said vehicle and an independently pivoted armature for said device, a magnetic device on said track, a train controlling mechanism, said vehicle device when moved in response to said track device, operating said controlling mechanism and said armature when

moved cooperatively with said vehicle device, preventing said operation.

29. In a railway traffic controlling system, the combination of a track, a vehicle thereon, a pivotally supported magnetic device on said vehicle and an independently pivoted armature for said device, a magnetic device on said track, a train controlling mechanism including a timing device, said vehicle device responding to said track device to operate said controlling mechanism and said armature responding to said vehicle device and arranged to operate said timing device.

30. In a railway traffic controlling system, the combination of a track divided into blocks, a vehicle thereon having a controlling mechanism, means on said trackway producing a magnetic field controlled by said blocks, a device on said vehicle responding inductively to said magnetic field, and a relay responding to said vehicle device and having a neutral and a polarized armature, said armatures controlling said mechanism.

31. In combination, a railway train, a generator on said train and having a field and an armature, means located in the trackway for supplying said field with magnetic flux of one relative polarity or the other in accordance with traffic conditions, means on the train for driving said armature, and train governing apparatus responsive to the polarity of the electromotive force supplied by said generator.

32. In a railway traffic controlling system, the combination of a track divided into blocks, a vehicle on the track having a controlling mechanism, means on the trackway producing a magnetic field energized by direct current and controlled by said blocks, a device on said vehicle responding inductively to said trackway field, a relay on said vehicle having a polarized armature responding to said device and a circuit established by said polarized armature for holding said armature in the position to which it has been moved.

33. In an electro-magnetic inductive system, the combination, a magnet having a pair of poles, a generator having a pair of poles comprising a field magnet, said generator poles aligning with but mechanically separated from the poles of the magnet and inductively magnetized exclusively by the poles of the magnet, an armature mechanically rotated between the poles of said generator and a circuit connected with said armature and energized exclusively by the field created by said magnet.

34. In an electro-magnetic inductive system, the combination, a magnet having poles, a circuit for energizing said magnet, a generator having a rotating armature and means for producing a magnetic field through said armature, said means being mechanically separated from said magnet poles and in-

ductively magnetized only by said magnet poles and a circuit connected with said armature and having the characteristics exclusively of the circuit energizing said magnet.

⁵ Signed at New York city, in the county of New York and State of New York, this 15th day of Aug., A. D. 1921.
